UNITED STATES PATENT OFFICE.

WALTER MERVILLE AUSTIN, OF SWISSVALE, PENNSYLVANIA, ASSIGNOR TO THE WESTINGHOUSE AIR BRAKE COMPANY, OF PITTSBURG, PENNSYLVANIA, A CORPORATION OF PENNSYLVANIA.

ENGINEER'S VALVE FOR AIR-BRAKES.

No. 882,608.

Specification of Letters Patent.

Patented March 24, 1908.

Application filed October 29, 1903. Serial No. 179,043.

To all whom it may concern:

Be it known that I, WALTER MERVILLE AUSTIN, a citizen of the United States, residing at Swissvale, in the county of Allegheny and State of Pennsylvania, have invented certain new and useful Improvements in Engineer's Valves for Air-Brakes, of which the following is a full, clear, and exact description.

10 This invention relates to fluid pressure train brakes and has special reference to the device commonly known as the "engineer's valve."

The object of my invention is to provide 15 an engineer's valve capable of automatically maintaining any pressure in the train pipe system that has once been determined by a definite movement of the valve handle. With such an engineer's valve, in case leakage occurs from the train pipe after a given reduction has been made to apply the brakes, such leakage will be instantly responded to by the engineer's valve and the train pipe charged from the main reservoir to compensate for the leakage. Likewise if for any 25 reason a pressure beyond that predetermined by the engineer's valve, enters the train pipe, the valve will automatically discharge the excess pressure and prevent the tendency of 30 the system to release the brakes. To accomplish these functions, my improved valve is so constructed that the pressure in the train pipe is balanced against a constant pressure or force, so that when one of the pressures is 35 greater than the other, the preponderating pressure determines whether a valve shall be opened to charge the train pipe, or another shall be opened to exhaust the train pipe. My valve also is constructed so that the 40 manipulator will know that when he moves the handle to a certain notch, a corresponding pressure will be established in the train pipe, whether that movement is to increase or decrease the pressure therein. Thus in 45 the application of brakes, the engineer will know that when he moves the handle to the first notch, he will effect a reduction say, two pounds, and that this reduction will be maintained as long as the valve handle remains in the first notch. Likewise if he moves the handle to the second notch, the 50 pressure will be further reduced by two pounds

and so maintained. In like manner each notch indicates a train pipe pressure and the engineer is not required to exercise judgment or depend upon his gage in charging or discharging the train pipe.

The construction of a valve adapted to accomplish this object will now be described in detail with reference to the accompanying drawing, in which:

Figure 1 is a section of an engineer's valve, some portions being on a slightly different plane from others; Fig. 2 is a half section and half elevation, the view being at right angles to Fig. 1; Fig. 3 is a plan of the valve with the handle partially broken away; Fig. 4 is a plan of the valve with the top removed and showing the valve seat, and Fig. 5 is a plan of the movable portion of the manually operated valve which rests upon the valve seat, Fig. 4.

The valve casing is made up of the parts A, B, C and D. A and B are bolted together and clamped between them is a disk E constituting the main valve seat. B and C are bolted together and D is connected to C by being threaded on an internal plug *p* common to both. The joints between the sections of the casing are carefully packed to avoid leakage. The part A is a cap and the main valve handle F is pivoted therein, the shaft of the handle projecting through the cap and carrying a dovetailed lug *f* which engages with a valve disk *a* resting upon the valve seat E and adapted to rotate thereon when moved by the handle. Around the outer edge of the cap A is formed a quadrant plate *b* having notches to be engaged by a spring bolt in the handle to hold the latter at any desired point. Each notch corresponds to a certain train pipe pressure, as will hereinafter appear. The shoulders at each end of the plate indicate the full release position and the emergency position, respectively.

The valve disk *a* is provided on its under side with two large cavities *a'* and *a''*, respectively; also with two concentric grooves *a'* and *a''*, respectively. On the face of the valve seat E there is a cavity *e*, a port *e'* leading through the casing section B to the main reservoir connection MR; also a port *e''* leading through the casing section B to the train pipe connection TP; also a port *e'''* leading to

an opening AT to the atmosphere, also in the casing section B. This valve seat also contains in its face two concentric grooves e^4 and e^5 , respectively, the former connecting with the port e^2 , leading to the train pipe, and the latter connecting with the port e^3 , leading to the atmosphere. This valve seat also contains a series of vertical passages e^6 and a single vertical passage e^7 , the purpose of which 5 will appear hereinafter. It may be stated here, however, that the seven passages e^6 correspond respectively with seven of the notches in the quadrant plate b, as will hereinafter appear.

10 In the casing section B, there is a transverse valve chamber c closed at each end by the screw caps g, g, and containing two pistons h and i connected together by a stem j which carries a D-valve k. This valve faces a seat in which there is a port j' leading to the port e^2 and the train pipe passage, and another port j'' leading to port e^3 connected with the atmosphere. The pistons h and i have a free fit in the chamber c so that air can feed 20 around them. They are held at a neutral or central position by springs l at each end. Chamber c communicates through a passage m with the cavity e in the valve seat E.

25 In the casing section C I place a series of nine flat rings o, one on top of another, between which are clamped the edges of a series of eight flexible diaphragms which are numbered from 1 to 8. The middle portions of these diaphragms are clamped between a series of nine disks q, which are placed upon a vertical stem q' and clamped together. The disks are of successively increasing external diameter and the rings are of successively increasing internal diameter, so that the exposed surface of each successive diaphragm 30 is to a predetermined extent greater than that of the diaphragm which immediately precedes it. The seven vertical passages e^6 in the valve seat E are individually continued through the casing section B, respectively to seven of the rings o, in the manner shown by the passage marked o' in Fig. 2. The single vertical passage e^7 in the valve seat, leads to the uppermost ring o. Each passage o' is continued through the ring to which it leads by a radial passage o² leading to the space between the two diaphragms clamped on each side of that particular ring. The radial passage in the upper ring leads to the space above the 40 upper or smallest diaphragm, which space is extended to a chamber o³ above the topmost disk.

45 Surrounding the stem q' is a spiral spring s seated at one end against the plug p and bearing at the other end against the lowest disk q, thus tending to move the stem upward.

The lower casing section D contains a small valve r seating upward and controlling

5 a passage r' leading from the space at the left of piston i to the atmosphere through the chamber r² and port r³. The lower end of stem q' projects through plug p in a position to strike and open valve r.

10 The upper end of stem q' occupies a similar position with respect to another small valve t, opening upwardly. This valve controls a passage t' leading from the space at the right hand end of piston h to the chamber o³ above the topmost disk q.

15 The operation is as follows: The parts are shown in full release or recharging position, it being understood that the position of the valve disk a upon the valve seat E is as if Fig. 5 were moved over to a concentric position on Fig. 4 without rotation. In this position cavity a' connects together ports e^1 and e^2 , thus connecting the main reservoir directly to the train pipe to quickly recharge the latter. Cavity e is also connected with port e^1 thus admitting main reservoir pressure through passage m into the valve chamber c containing pistons i and h. Groove a³ connects together the vertical passage e^7 and groove e^4 , thus admitting train pipe 20 pressure to the chamber o³ above the upper or No. 1 diaphragm. The other vertical passages e^6 are all connected with the port e^3 and the atmosphere through the grooves a⁴ and a⁵.

25 When train pipe pressure has risen to the full running pressure, the brake handle should be moved to the first notch on plate b, thus closing direct communication between main reservoir and train pipe. This is the running position and in this condition the train pipe pressure in the chamber o³ above the topmost disk balances the opposing pressure of spring s and valve stem q' occupies a neutral position with respect to both of the valves r and t, which are both closed.

30 To make a service application of brakes, the engineer will move the handle F to the next notch, or to any notch whose corresponding train pipe pressure is what is necessary to make the service stop. In thus moving the handle, disk a is rotated until groove a³ uncovers one or more of the vertical passages e^6 , depending upon the notch at which the handle was placed. This leaves the main reservoir connected with the double piston chamber through e^1 and m. Train pipe pressure then flows from the port e^2 through grooves e^4 , a³, passage e^7 , as before, and as many of the passages e^6 as were uncovered by groove a³, and let it be now assumed that only 35 one of said passages e^6 was uncovered. From the first passage e^6 the train pipe pressure leads through the radial passage o² in the second ring and enters the annular space between the diaphragms 1 and 2. The pressure under diaphragm 1 is balanced by the same pressure acting upon the same area.

303. FLUID PRESSURE BRAKE & ANALOGOUS SYSTEM

- above it, but the pressure above diaphragm 2, being upon a larger area, adds a predetermined amount to the total downward pressure which overcomes spring s and stem 5 q' is forced downward, thus opening valve r and permitting the main reservoir pressure to escape from the space at the left of piston i . Piston stem j then moves to the left, compressing spring g and causing the **D**-valve 10 k to connect passage j' (train pipe) with passage j^2 (atmosphere). The reduction which then takes place in the train pipe is felt simultaneously in the space between diaphragms 1 and 2, and as soon as a reduction 15 has been made which compensates for the excess of area of diaphragm 2 over diaphragm 1, spring s overcomes the downward pressure and returns the stem to the neutral position, allowing valve r to close. When 20 this takes place, the pressure in the double piston chamber flows around piston i and equalizes on each side thereof permitting spring g to return the pistons to the neutral position and cut off train pipe passage j' 25 from the atmospheric passage j^2 . If a further reduction of train pipe pressure is required, say to the amount corresponding to the fourth notch from running position, the handle is moved to the fourth notch position 30 and this uncovers the first four of the passages e^6 and admits train pipe pressure on both sides of the diaphragms 1, 2, 3 and 4, but on the upper side only of 5. Valve stem q' will then again move downward and open valve 35 r , which will stay open until train pipe pressure had been reduced enough to compensate for the total increase of diaphragm area, whereupon the force acting upon the valve stem will again see a balance and close valve 40 r and the atmospheric escape from the train pipe. Thus said diaphragm exposed to the train pipe pressure will permit a corresponding reduction of train pipe pressure and thus it is that the engineer knows that when he 45 moves the handle to a given notch, a given reduction will be made in the train pipe. If now, while the handle is at a given notch, there should occur a leakage from the train pipe system, then the total train pressure 50 acting against the spring s will not be so great as at the moment when the stem last found its balance; hence, the spring will move the stem upward and open valve t , allowing pressure to escape from the right hand side of piston h through passage t' , chamber o^3 , passage o^2 in the topmost ring, passage e^7 , groove a^3 and e^4 to the train pipe. The pistons will move to the right, causing the **D**-valve to uncover train pipe passage j' 55 60 and admit main reservoir pressure from the piston chamber c into the train pipe to compensate for the leakage. When this compensation has taken place, valve stem q' will be again balanced and will move downward to its neutral position allowing valve t to 65 close, whereupon the equalizing of pressure in the piston chamber will permit the pistons to be moved by the spring g to the central or lap position, closing communication between the main reservoir and train pipe. 70 Hence the leakage from the train pipe system is automatically compensated for without any action on the part of the engineer.
- If, for any reason, after a given reduction, the train pipe pressure should be augmented 75 from any source, it will be seen that the increased pressure having access to the diaphragms, will again unbalance stem q' and force it downward to open valve r . This will be followed by the same operation as 80 before, the train pipe being exhausted by the movement of the **D**-valve until a balance is again effected.
- If it is desired to increase the pressure in the train pipe to a point below full running 85 train pipe pressure, the brake handle is moved toward release position to the notch corresponding to the increased pressure desired. Let this notch, for example, be 3rd notch from running position, then the first three of passages e^6 will be in communication with train pipe, as previously explained. The remaining passages will be in communication with the atmosphere. All diaphragms below four are now connected with 90 the atmosphere. The area of the diaphragm exposed to train pipe pressure is now smaller than it was when the balance between spring s and pressure on diaphragm was last established. Spring s will overcome the pressure 100 on diaphragm causing stem q to move upwards and unseat valve t ; and slide valve k will move to admit pressure from main reservoir to train pipe, as previously described, when the balance between train pipe pressure 105 on diaphragm and spring s was disturbed by leakage from the train pipe. This recharging of train pipe will continue until a new balance between pressure on diaphragm and spring s is established, when further flow of 110 pressure into the train pipe will be prevented, as previously described.
- In the release of brakes, the valve handle is turned to the full release position shown in Fig. 3, which rotates the valve disk a to the 115 position first described, and thus connects all of the passages e^6 with the atmosphere through groove a^4 , groove e^5 , which it just overlaps, and port e^3 . Passage e^7 is connected with the train pipe port e^2 through 120 grooves a^3 and e^4 and the train pipe is connected with the main reservoir through port e' , cavity a' and port e^2 , thus restoring pressure to the train pipe and also restoring the normal train pipe pressure to the chamber o^3 125 above the top diaphragm, which retains the valve stem q' in its balanced and neutral position.

The engineer should now, as before stated, move the handle to the first notch or running position, but if he fails to do so, when full running pressure has been attained, the 5 increased downward pressure of train pipe fluid on diaphragm No. 1 will overcome spring s allowing valve t to close and opening valve r . Pressure will now flow through passage r' and valve r and port r^3 from cavity 10 back of piston i to atmosphere. Main reservoir pressure, which has now leaked by piston h , will move valve stem j and slide valve k , and open communication through port j' , valve k , port j^2 to port e^3 , thence to atmosphere, thus preventing the train pipe from 15 being overcharged.

When the handle is in running position, cavity e is still in communication with port e' and we have main reservoir pressure in valve 20 chamber c containing pistons i and h . Any decrease of train pipe pressure below full running valve pressure will be restored in the following manner: The pressure on diaphragm No. 1 being less than full running 25 train pipe pressure, spring s will preponderate and stem q will move upward unseating valve t , thus opening chamber back of piston h to train pipe through passage t' , valve t and passage e' , groove a^3 , groove e' and port 30 e^2 . Pistons h and i and stem j will move to the right under main reservoir pressure on piston i , against train pipe pressure on piston h , causing valve k to uncover port j' , admitting pressure from main reservoir through 35 port e' , cavity a' , cavity e , passage m , port j and port e^2 to train pipe. When train pipe pressure has increased to full running valve, train pipe pressure on diaphragm No. 1 will 40 overcome spring s , causing stem q' to move downward allowing valve t to seat, thus closing passage t from chamber behind piston h ; main reservoir pressure will now leak by piston h until the pressures on both sides of piston h are equalized, when spring l will 45 push stem k' and valve k to central position covering port j' and preventing further pressure from flowing into train pipe.

In making an emergency reduction, the 50 valve handle is thrown to the extreme opposite position to that shown in Fig. 3, whereupon train pipe port e^2 is directly connected with atmospheric port e^3 through the cavity a^2 and communication from main reservoir to chamber c containing pistons h and i , is 55 cut off by the movement of the rotary valve to a position where a plain portion of the valve surface covers cavity e . It is now impossible for pressure from main reservoir to get into train pipe regardless of the position 60 of valve k . The reduction of train pipe pressure is therefore made instantly through the atmospheric passage, to which it is opened by the rotation of the disk and serves its purpose of meeting the emergency more

perfectly than if the reduction was effected 65 through the D-valve in the same manner as in service applications.

I wish it to be understood that the spring s merely represents a constant force opposing train pipe pressure and that as such, any 70 other constant or substantially constant force, may be substituted. It is likewise obvious that an arrangement of sliding pistons can be substituted for the diaphragms 1 to 8. It is likewise understood that I may vary the 75 size and number of the annular rings, circular disks and diaphragms to suit the requirements of any individual case.

The utility of this engineer's valve is emphasized when used in a system containing 80 triple valves adapted to fractionally increase or decrease the pressure in the brake cylinders at the will of the engineer, such a triple valve being described in my companion application Serial No. 178,339 filed Oct. 24th 85 1903. The ability to increase or decrease train pipe pressure at will during an application of brakes without first releasing the brakes, is a very important improvement in 90 air brake apparatus, which is accomplished in the most perfect manner by a combination of the engineer's valve described herein and the triple valve described in the said companion application.

Having described my invention, I claim:— 95

1. In a fluid pressure brake, the combination with a train pipe and an engineer's brake valve having a plurality of positions, of a mechanism for altering the train pipe pressure and operated by opposing forces, one of which is derived from the train pipe pressure, and means controlled by the movement of the engineer's brake valve to its different positions for varying the effective resultant of 100 the force due to train pipe pressure.

2. In a fluid pressure brake, the combination with a train pipe and an engineer's brake valve having a plurality of positions, of a valve device for controlling the charging and discharging of the train pipe, and operated 110 by the train pipe pressure in one direction and an opposing constant force, and means controlled by the movement of the engineer's brake valve to its different positions for varying the effective resultant of the train pipe 115 pressure acting on said valve device.

3. In a fluid pressure brake, the combination with a train pipe, of a mechanism for altering the train pipe pressure and normally balanced by the opposing forces of said train 120 pipe pressure and a constant force, and means whereby such balance is automatically maintained at any predetermined degree of train pipe pressure.

4. In a fluid pressure brake, the combination of a spring having a constant force, means for balancing different train pipe pressures against said force, and means whereby

303. FLUID PRESSURE
& ANALOGOUS SY

882,608

5

such balance is automatically maintained at any predetermined degree.

5. In a fluid pressure brake, the combination with a train pipe and an engineer's brake valve having a plurality of positions, of a valve mechanism for altering the train pipe pressure and normally balanced by the opposing forces of said train pipe pressure and a constant force, and means operated by the 10 movement of the engineer's brake valve to a given position for automatically maintaining such balance at a corresponding predetermined degree of train pipe pressure.

6. In a fluid pressure brake, the combination with a train pipe, of an engineer's brake valve device comprising a main valve mechanism for controlling the charging and discharging of the train pipe, and an auxiliary valve means for controlling the action of said 20 main valve.

7. In a fluid pressure brake, the combination with a train pipe, of an engineer's brake valve device comprising a main valve mechanism for controlling the charging and discharging of the train pipe, and an auxiliary valve mechanism controlled by the movement of the brake valve handle for governing 25 said main valve.

8. In a fluid pressure brake, the combination with a train pipe, of an engineer's brake valve device comprising a main valve mechanism for charging and discharging the train pipe, a piston for actuating said valve mechanism, and an auxiliary valve means for 30 controlling the fluid pressure acting on said piston.

9. In a fluid pressure brake, the combination with a train pipe, of an engineer's brake valve device comprising a main valve mechanism for charging and discharging the train 40 pipe, a piston for actuating said valve mechanism, a movable abutment subject to train pipe pressure, and auxiliary valve means operated by said abutment for controlling the pressure acting on said main piston.

10. In a fluid pressure brake, the combination with a train pipe, of an engineer's brake valve device comprising a main valve mechanism for charging and discharging the train 50 pipe, a piston for actuating said valve mechanism, a movable abutment subject to the opposing pressure of the train pipe and a spring, and auxiliary valve means operated by said abutment for controlling the action of said main piston.

11. In a fluid pressure brake, the combination with valve mechanism for reducing train pipe pressure, of a movable abutment subject to train pipe pressure for governing the 60 action of said valve mechanism, and means for varying the effective area of said abutment exposed to train pipe pressure.

12. In a fluid pressure brake, the combination with valve mechanism for reducing train

pipe pressure, of a movable abutment subject to train pipe pressure for governing the action of said valve mechanism, and means operated by the movement of the engineer's valve for varying the effective area of said abutment exposed to train pipe pressure. 65

13. In a fluid pressure brake, the combination with a valve means for controlling the charging and discharging of the train pipe, of a movable abutment subject to train pipe pressure for governing the action of said valve means, and means operated by the movement of the engineer's valve for varying the effective area of said abutment exposed to train pipe pressure. 70

14. In a fluid pressure brake, the combination with a valve mechanism for controlling the discharge from the train pipe, of a movable abutment for governing the action of said valve mechanism and subject to the opposing pressures of the train pipe and a constant force, and means for varying the effective area of said abutment exposed to train pipe pressure. 80

15. In a fluid pressure brake, the combination with a valve mechanism for controlling the discharge from the train pipe, of a movable abutment for governing the action of said valve mechanism and subject to the opposing pressures of the train pipe and a constant force, and means operated by the movement of the engineer's valve for varying the effective area of said abutment exposed to train pipe pressure. 85

16. In a fluid pressure brake, the combination with valve means for controlling the charging and discharging of the train pipe, of a movable abutment for governing the action of said valve means and subject to the opposing pressures of the train pipe and a constant force, and means operated by the movement of the engineer's valve for varying the effective area of said abutment exposed to train pipe pressure. 100

17. In a fluid pressure brake, the combination with a main valve device for varying train pipe pressure and an auxiliary valve for controlling the action of said main valve, of a movable abutment subject to train pipe pressure for operating said auxiliary valve, and means for varying the effective area of said abutment exposed to train pipe pressure. 110

18. In a fluid pressure brake, the combination with a main valve device for varying train pipe pressure and an auxiliary valve for controlling the action of said main valve, of a movable abutment subject to train pipe pressure for operating said auxiliary valve, and means operated by the movement of the engineer's valve for varying the effective area of said abutment exposed to train pipe pressure. 120

19. In a fluid pressure brake, the combina-

tion with a main valve for altering train pipe pressure, and an auxiliary valve for controlling the action of said main valve, of a movable abutment subject to the opposing pressures of the train pipe and a constant force for operating said auxiliary valve, and means for varying the effective area of said abutment exposed to train pipe pressure.

20. In a fluid pressure brake, the combination with a main valve for altering train pipe pressure, and an auxiliary valve for controlling the action of said main valve, of a movable abutment subject to the opposing pressures of the train pipe and a constant force 10 for operating said auxiliary valve, and means operated by the movement of the engineer's valve for varying the effective area of said abutment exposed to train pipe pressure.

21. An engineer's valve, comprising means 20 for charging and discharging the train pipe, said means being held in a neutral condition by a balancing of train pipe pressure against a constant force independent of the movement of the engineer's valve and being 25 moved to either charge or discharge the train pipe by a yielding or preponderance of train pipe pressure with respect to said constant force.

22. An engineer's valve, comprising means 30 for charging and discharging the train pipe, said means being held in a neutral condition by balancing train pipe pressure against an opposing constant force independent of the movement of the engineer's valve, and being 35 moved to either charge or discharge the train pipe by a disturbance of the balance in favor of said opposing constant force or train pipe pressure.

23. An engineer's valve, comprising a 40 valve having movements in two directions, one to charge and the other to discharge the train pipe, in combination with two valves, one adapted to control pressure to move said first mentioned valve in one direction and the 45 other adapted to control pressure to move said valve in its other direction, and a movable element adapted when moved in one direction to open one of said two valves, and when moved in the other direction to open 50 the other of said two valves, said movable element being exposed to a constant force on one side and to train pipe pressure on the other side.

24. An engineer's valve, comprising a 55 valve having movements in two directions, one to charge and the other to discharge the train pipe, in combination with two valves, one adapted to control pressure to move said first mentioned valve in one direction and 60 the other adapted to control pressure to move said valve in its other direction, and a movable element adapted when moved in one direction to open one of said two valves, and when moved in the other direction to open

the other of said two valves, said movable 65 element being exposed to a constant force on one side and to train pipe pressure on the other side and means for varying the area of said movable element exposed to said train pipe pressure.

25. An engineer's valve, comprising means 70 for altering train pipe pressure, in combination with a movable element controlling the actuating of said means, said movable element being exposed on one side to a constant 75 force and on the other side to train pipe pressure and means for varying the effective area of said movable element exposed to train pipe pressure.

26. An engineer's valve, comprising means 80 for charging and discharging the train pipe, in combination with a movable element adapted to control said charging and discharging means, said movable element consisting of a stem having attached thereto a 85 series of diaphragms of graduated area, a constant force acting upon said stem to move it in one direction and means for directing air pressure against any desired number of said diaphragms in opposition to said constant force.

27. An engineer's valve, comprising means 90 for charging and discharging the train pipe, in combination with a movable element adapted to control said charging and discharging means, said movable element consisting of a stem having attached thereto a 95 series of diaphragms of graduated area, a constant force acting upon said stem to move it in one direction and means for directing 100 train pipe pressure against any number of said diaphragms in opposition to said constant force.

28. An engineer's valve, comprising means 105 for charging and discharging the train pipe, in combination with a movable element adapted to control said charging and discharging means, said movable element consisting of a stem having attached thereto a series of diaphragms of graduated area, a constant 110 force acting upon said stem to move it in one direction and manually operated means for directing air pressure against any desired number of said diaphragms in opposition to said constant force.

29. In an engineer's valve, a chamber containing main reservoir pressure and a valve balanced on opposite sides by said pressure, said valve controlling the charging and discharging of the train pipe, exhaust passages 120 leading from the opposite sides of said valve, a valve in each passage and a movable element controlling both valves in said passages and itself controlled by train pipe pressure.

30. In an engineer's valve, a chamber containing main reservoir pressure and a valve balanced on opposite sides by said pressure, 125 springs tending to hold the valve at a neutral

position, said valve controlling the charging and discharging of the train pipe, exhaust passages leading from the opposite sides of said valve, a valve in each passage and a 5 movable element controlling both valves in said passages and itself controlled by train pipe pressure.

31. In an engineer's valve, a movable element controlling the charging and discharging of the train pipe, said element being exposed on one side over a given area to train 10

pipe pressure and being exposed on the other side to a constant force, in combination with means for increasing the area exposed to train pipe pressure, for the purpose set forth. 15

In witness whereof, I subscribe my signature, in presence of two witnesses.
